[57] ABSTRACT

A packerhead/vibration system concrete pipe machine having an overfill and compaction ring assembly mounted on top of the pipe mold enabling complete formation of the concrete pipe in one stage without need of adding extra concrete to the top of the mold to make up for volume lost in inherent compaction of material caused by vibration. A method of vibratory concrete pipe manufacture including the steps of overfilling the pipe mold in the pipe forming process, vibrating the concrete forming the pipe, and compressing the overfill concrete into a space created by densification of the pipe material caused by vibration.

CROSS REFERENCE TO RELATED APPLICATION

A portion of the disclosure of this application comprises the subject matter of a copending application entitled CAP REST ASSEMBLY FOR PACKERHEAD/VIBRATION SYSTEM CONCRETE PIPE MACHINE, filed Apr. 19, 1973, Ser. No. 352,672 Ronald J. Walchek, inventor, and assigned to the same assignee as this application.

BACKGROUND OF THE INVENTION

The subject matter of this application includes significant improvements to concrete pipe making machines disclosed and claimed in U.S. Pat. No. 3,655,842, issued Apr. 11, 1972, entitled METHOD OF VIBRATING CORE IN CONCRETE PIPE MAKING MACHINE and U.S. Patent Application Ser. No. 867,344 filed Oct. 17, 1969 now U.S. Pat. No. 3,752,626, entitled VIBRATORY CORE FOR CONCRETE PIPE MAKING MACHINE. Both patent and application are assigned to Viropac, Inc., of Sioux City, Iowa. While the subject matter of the present application is particularly useful with the invention disclosed and claimed in the above referenced patent and patent application, it is equally useful with any of the wide variety of concrete pipe machines currently on the market, particularly those employing a vibrating process, as will become readily apparent below.

Referring to the above identified method patent, FIGS. 1-5 inclusive thereof disclose a concrete pipe machine employing a vibrating core. Initially the packerhead and core are locked together. The pipe is then formed by passing packerhead and core upwardly through a vertically disposed pipe mold or jacket while simultaneously discharging virtually dry or zero slump concrete into the annular space between the jacket and core (FIGS. 1-3 of the method patent). Upon reaching the stage indicated in FIG. 4 of the method patent the pipe has been completely formed.

However, the desired vibration, which eliminates voids and substantially densifies the pipe during formation, yields a green pipe with insufficient concrete at the top end of the pipe mold to completely form the spigot end of the pipe. Quite naturally, this condition is caused by the necessary and desirable vibration occurring during and after the formation of the pipe. As voids are filled and the pipe densifies, the level of concrete falls, or "slumps" into the mold cavity. This could cause a crack in the spigot end together with downward displacement of the snap ring (which is normally present and used for forming a seal ring groove in the spigot end) thus yielding a useless pipe section. An initial attempt to solve this problem was to make an extra sub-pass of packerhead and core, and adding supplemental concrete from the boot and conveyor in order to complete the pipe as set forth in the method patent. However, this extra operation not only left a mark internally of the pipe slightly below the spigot end, but also was a time consuming operation, in an industry where extra time in forming each pipe results in an unduly burdensome expense. Specifically, performance studies have been done in this industry, and have shown that manufacture of pipe by a vibratory method takes significantly longer than a non-vibratory method, but the cost is tolerated because the finished product is more desir-

able. However, to keep manufacturing costs competitive, increases in time required in the manufacture of pipe by a vibratory process must be avoided.

The present invention overcomes these problems by providing a downwardly driven additional ring assembly on top of the pipe mold to accommodate a slight overfilling of the mold in initial pipe making the ring assembly including a movable compaction ring above the overfill level of concrete for compressing the overfill into the pipe mold as vibration continues. When used with open bore caps the compaction ring serves to form a smooth spigot end to the pipe and when used with closed bore caps, it acts directly on the cap, which will form the spigot end.

Briefly stated, the present invention fills the slump created during the process of forming pipe by a packerhead/vibration system concrete pipe machine, permits green pipe to be made in one continuous operation, and is becoming known in the trade as a "Slump Filler."

SUMMARY OF THE INVENTION

It is a primary object of this invention to provide a slump filler ring structure adapted to fit on top of the pipe mold of a packerhead/vibration system concrete pipe machine to permit overfill of the mold during the pipe filling process and subsequent compaction of material into the desired pipe section.

It is an object of the invention to provide a slump filler assembly for a packerhead/vibration system which is simple in construction and easily adaptable to a wide variety of existing machines.

It is another object of the invention to provide a slump filler apparatus for a packerhead/vibration system wherein the slump filler may be employed for either closed bore caps or open bore caps.

Yet another object of the invention is to provide a slump filler apparatus for a packerhead/vibration system wherein a compaction ring is provided for acting on the concrete directly when used with an open bore cap or against the cap ring proper when used with a closed bore cap.

Still another object of the invention is to provide a slump filler apparatus for a packerhead/vibration system wherein the holdown cylinders of the system may be employed to actuate the slump filler.

A further object of the invention is to provide a slump filler apparatus for a packerhead/vibration system having fluid pressure actuating means operable in conjunction with the system's holdown cylinders in one embodiment, or independently of the system in another embodiment.

A still further object of the invention is to provide a slump filler apparatus for a packerhead/vibration system wherein the slump filler is located beneath and outside of the concrete hopper on top of the pipe mold, so the slump filler is protected from the concrete and the hopper interior is left free for other equipment, such as an automatic hopper cleaner.

Yet a further object of the invention is to provide a slump filler apparatus for a packerhead/vibration system which employs the guides of the existing hopper located on top of a pipe mold for operation, thereby providing a compact, simple structure utilizing already existant other structure for support and actuation.

It is a further primary object of the invention to provide an apparatus for concrete pipe forming by a packerhead/vibration system wherein a green pipe is formed

by filling the mold with concrete, including overfilling the mold, simultaneous and subsequent vibration, and mechanical compaction to reduce the material into the desired finished product.

It is yet another object of the invention to provide an apparatus for concrete pipe forming by a packerhead/vibration system wherein a green pipe is formed by an overfill-vibration-mechanical compaction method in single, double or further multiple pass processes.

BRIEF DESCRIPTION OF DRAWINGS

Preferred structural embodiments of this invention are disclosed in the accompanying drawings in which:

FIG. 1 is a front elevation view of one commercial embodiment of a concrete pipe machine;

FIG. 2 is a top view of the machine shown in FIG. 1; FIGS. 2A and 2B are schematic views similar to FIG. 2 showing machines set up for right hand and left hand operations, respectively;

FIG. 3 is a side elevation view of another commercial embodiment of a concrete pipe machine, similar to the embodiment shown in FIG. 1 in most respects, and further showing a packerhead/vibration system employing a rollerhead; the view is partly in section with parts broken away to show interior details;

FIG. 4 is an enlarged scale front elevation view of the vibrating core, hopper and rollerhead shown in FIG. 3 and further illustrating one embodiment of the slump filler the view being partly in section with parts broken away to show interior detail, and showing relationship of parts just prior to actuation of the slump filler being used with an open bore cap;

FIG. 5 is an enlarged detail view similar to the upper one-third of FIG. 4 but showing relationship of parts just after completion of a compaction operation by the slump filler as used with an open bore cap;

FIG. 6, is a greatly enlarged detail, partial section view of the upper left hand portion of FIG. 5, showing one of a series of hydraulic ram actuators for the slump filler;

FIG. 7 is a view similar to FIG. 6 but showing relationship of parts after actuation of the slump filler;

FIG. 8 is an enlarged detail section view of one hydraulic ram actuator taken along lines 8-8 of FIG. 7;

FIGS. 9 and 10 are detail views similar to FIGS. 6 and 7, respectively, but illustrating another embodiment of the invention, used with a closed bore cap;

FIGS. 11 and 12 are detail views similar to FIGS. 9 and 10, respectively, but showing a novel cap rest assembly, the subject matter of the copending application Ser. No. 352,672 noted above;

FIG. 13 is a detail end view of a cap rest member, taken along lines 13-13 of FIG. 11;

FIG. 14 is an enlarged detail section view showing the left hand portion of the slump filler being used in manufacture of steel end ring non-cylinder wire reinforced concrete pipe;

FIG. 15 is a greatly enlarged elevation view of another cap rest assembly;

FIG. 16 is a partial section view taken along lines 16-16 of FIG. 15;

FIG. 17 is a view in perspective of another embodiment of a slump filler;

FIG. 18 is a partial section view taken along lines 18-18 of FIG. 17; and

FIG. 19 is a view similar to FIG. 5, illustrating use of the embodiment of the slump filler shown in FIGS. 17 and 18.

DESCRIPTION OF THE PREFERRED EMBODIMENTS

As stated above, the slump filler of the instant invention is readily adaptable to any one of a wide variety of existing concrete pipe machines employing a packerhead/vibration system. However, in discussing preferred embodiments of the invention in this specification, reference will be made only to one specific type of machine currently on the market.

Specifically, the slump filler is illustrated and discussed with reference to a concrete pipe machine utilizing a packerhead/vibration system which is disclosed and claimed in the method patent and apparatus patent application Ser. No. 867,344 noted above. Currently, this machine is known and marketed as a "McCracken" packerhead machine, employing a "Viro-pac" supplemental vibration system, both being manufactured and sold by the assignee of this application.

Referring now to FIG. 1, a "McCracken" concrete pipe machine is shown, minus a pipe mold and "Viro-pac" unit and core for clarity of the figure. The pipe machine 10 is mounted over a pit 12 and includes a frame superstructure 14, a packershaft 16 depending from crosshead 18, mounted for vertical movement along a pair of guide tubes 20, and a pair of hydraulically actuated lift rams 22 acting on support struts 24 of a crosshead 18 for raising and lowering crosshead 18. Beneath cross frame 26 is a pipe jacket hopper 28, guided vertically by a pair of hopper guide tubes 30, and lowered by means of a pair of holdown cylinders and piston rod assemblies 32. In this embodiment, an operator's platform 34 is attached to one side of hopper 28 and includes a control panel 36. In other machines, the operator's platform and control panel may be mounted elsewhere, for example, at the level of cross frame 26 on one side of machine 10. A pair of lift rods 38 fixed to and extending above hopper 28, are mounted slidably through struts 24 of crosshead 18 and have lift blocks 40 at their upper, terminal ends. Thus, when a pipe forming operation has been completed, crosshead 18 is lifted to the position shown in phantom lines in FIG. 1. During the upward travel of crosshead 18, struts 24 will engage blocks 40 and lift the hopper 28 off of the pipe mold or jacket therebeneath (not shown) so that the pipe jacket and the pipe formed therein may be removed from the machine 10.

The pipe jacket is placed on a turntable 42 (FIGS. 1 and 2) which includes mounting stations 44, 46 for the pipe jackets. The pair of stations 44 differ in diameter from stations 46 so that turntable 42 may accommodate varying sizes of pipe jackets, depending on the size of the pipe to be produced. At any one time, only one pair of stations will be used (44, in FIGS. 2, 2A and 2B) Thus, as one pipe jacket is being used to form pipe on one station 44, the other station 44 will be disposed 180° therefrom, in an off bearing position, where a completed pipe and pipe jacket may be removed, and an empty pipe jacket placed thereon. In this way production proceeds in a smooth, uninterrupted fashion.

FIGS. 2A and 2B are similar to FIG. 2, and illustrate "right hand" and "left hand" machines, respectively. In other words, depending upon the customer's requirements, the machine may be built so that turntable 42 rotates about the right front leg 48 (FIG. 1) of machine 10 or the left front leg (FIG. 2B).

Other parts of machine 10 illustrated in FIG. 2 include an electrical panel 50 with a cover door 52, hy-

draulic unit 54 for providing hydraulic fluid under pressure to the various hydraulically actuated components of machine 10, a concrete material boot 56 and material conveyor 58, for transporting material from boot 56 to hopper 28 and the pipe jacket (not shown).

Referring now to FIG. 3 a "Viropac" modified "McCracken" concrete pipe machine has a "Viropac" unit 60, "Viropac" core 62, and a rollerhead variety of packerhead 64 suspended from packer-shaft 16 depending from crosshead 18 on top of frame superstructure 14. The "Viropac" non-rotating core is mounted beneath turntable 14. The "Viropac" non-rotating core is mounted beneath turntable 42 on a core support platform 66 which moves vertically by means of a hydraulic piston cylinder actuator 68. Platform 66 is guided for vertical movement by a plurality of bearing block assemblies 70 attached to and supporting platform 66 and movable along a plurality (four, in this case) of stationary guide rods 72.

A pipe mold or jacket 74 rests on turntable 42 and, in this embodiment, has a bell end form section at the lower end, and a spigot end section at the top. Pipe jacket 74 may be either a single or multiple piece unit. A bell end pallet 76 (FIG. 4) is located concentrically interiorly at the base of jacket 74, directly above a bell down assembly 78, which is employed to raise, rotate and vibrate pallet 76 and consequently the material forming the bell end of the pipe section being made during the initial stages of forming a section of pipe.

As illustrated in FIG. 3, the machine is in the stage of operation wherein a fresh, green pipe 80 has been almost made. A detailed description and discussion of the entire process of manufacture up to this point appears in the method U.S. Pat. No. 3,655,842, referenced above. FIG. 4 of that patent is similar to FIG. 3 of this specification in showing the same stage of pipe manufacture.

At this stage of manufacture, all material has been placed in the jacket 74. Rollerhead 64 has ceased its operation, and has been detached from the non-rotating vibratory core 62 and raised above jacket 74. Or, depending on customer preference, rollerhead 64 may remain attached to core 62 during this time. At this point, core 62 continues to vibrate for a short period of time in order to assure complete consolidation, densification and elimination of any voids in the material forming green pipe 80.

It is at this stage of manufacture that the slump filler 82 (FIGS. 4 and 5) serves its intended purpose. Previously, the desirable core vibration caused material to settle or "slump" leaving an incomplete spigot end to green pipe 80. Even worse, vibration and slumping could cause a crack behind the snap ring and downward displacement of the snap ring. Prior to this invention these problems were solved by leaving rollerhead 16 locked to core 62, lowering the rollerhead and core slightly, and adding sufficient extra material from boot 56 and conveyor 58 to complete the spigot end of green pipe 80. This extra step was not only time consuming, but left objectionable finishing marks internally of the green pipe, near the spigot end. Furthermore, this vibration step again caused further slumping, resulting in a finished pipe of insufficient length, or a "short pipe." The only alternative was the extra abbreviated pass being made without vibration, but this left a finished pipe with an unvibrated spigot end. Neither result is really satisfactory.

Slump filler 92 overcomes these problems by permitting a slight overfill of material into jacket 74 when the pipe is initially formed, this overfill being illustrated in FIG. 4 at 84. Other components illustrated in this view 5 include one of a number of core vibrators 86, air hoses 88 therefor, hydraulic lines 90 for the core to rollerhead locking device 92 [disclosed in detail and claimed in U.S. Pat. No. 3,701,617, inventors and assignee being the same as in this application], longbottom 94 of 10 rollerhead 64, which rotates to trowel the mix and form the smooth interior of pipe 80 and turning and vibrating plate and standard assembly 95, used with bell down assembly 78 to form the bell end of the pipe as set forth above.

15 Slump filler 82 has a spigot end compaction and forming ring 96 which, as the step of core vibration continues after detaching and raising rollerhead 64, depresses the overfill 84 to consolidate and neatly form the spigot end of the pipe, all as illustrated in FIG. 5, 20 without need of adding additional material to jacket 74 to compensate for volume lost through material consolidation from vibration, as was previously done.

In the embodiment of the invention presently under discussion, the spigot end of the pipe is being formed by 25 employing an open bore cap ring. Specifically, open bore cap 98 with its snap ring 100 therein covers only about one-half of the outer, spigot end of pipe 80, the other half being formed by compaction ring 96. The embodiment employing closed bore caps will be discussed below.

In the present embodiment, compaction ring 96 is 30 welded to a short cylindrical dimension spacer ring 102, which is in turn welded to a filler ring 104 bolted to hopper bottom plate 106 which is a part of hopper 28. This entire unitary assembly is spaced above a stationary top centering ring 108 by a plurality of hydraulic ram actuators 110. Actuators 110 are of sufficient 35 capacity and distribution (in this embodiment, 3 circumferentially spaced actuators 110 are enough) to resist the downward force exerted by mold and hopper holdown cylinders 32, located on to each side of hopper 28.

As shown in FIG. 4, which is a view taken from the 40 front of the machine illustrated in FIG. 3, guide tubes 30 for hopper 28 are received through a pair of hopper guide tube bearing blocks 112, firmly bolted to either side of hopper 28 and having outer flanges to which are bolted the free ends of the piston rods of holdown cylinders 32 at the bottom, and the bases of lift rods 38 at 45 the top. Although the disposition of these parts of the machine varies slightly from their disposition disclosed in the embodiment illustrated in FIG. 1, their general structure and function remains the same.

During the step of compaction of the spigot end of 50 the pipe 80, pressure in rams 110 is relieved to allow holdown cylinders 32 to draw hopper 28, and consequently slump filler 82 with its compaction ring 96, downwardly towards top centering ring 108 so that parts reach the disposition indicated in FIG. 5. This figure 55 illustrates disposition of parts after the slump filler has served its purpose. That is, compaction ring 96 has its lower, finishing surface substantially flush with the interior, horizontal molding surface of open bore cap 98. At this point in the pipe manufacturing process, 60 green pipe 80 has been completely formed, densified by the desired vibration, and has a finished spigot end, formed smoothly and leaving a pipe section of the desired length. After the step illustrated in FIG. 5, core 62

is withdrawn from green pipe 80 and jacket 74, table 42 is rotated 180° to remove the finished pipe and its jacket while a fresh jacket is rotated into place beneath rollerhead 64, and the pipe manufacturing cycle is repeated.

FIGS. 6-8 illustrate the construction of hydraulic ram actuators 110. Each ram is secured in mounting block or blocks 114, firmly bolted to stationary top centering ring 108. A pair of adjustable retaining posts 116 each include a center rod 118, welded to and depending from filler ring 104, an adjustable guide sleeve and washer assembly 120, and a pair of lock nuts 122, threaded to the lower end of center rod 118. The sleeve of assembly 120 passes through a guide bore 124, (FIG. 8) formed in top centering ring 108. The lower limit of travel of slump filler 82 is determined by a spacer ring 126, welded to top centering ring 108, and having gap blocks 128 circumferentially spaced thereabout (FIG. 8). Blocks 128 provide a clearance area 130 for escape of material which might be forced about cap 98 during operation of slump filler 82. However, maximum separation between top centering ring 108 and filler ring 104 (FIG. 6) may be set by merely adjusting the vertical position of sleeve assemblies 120 along rods 118 by lock nuts 122. This adjustable mounting feature permits manufacture of ram units 110 in mass, regardless of the size of machine 10 with which they may be eventually used. It also permits adjustment by the customer to suit his conditions and requirements. In particular, the range of slump is about 1 1/4 inches under most conditions, but the customer may wish to increase or decrease this distance after experience with the machine.

The operation of slump filler 82 and ram units 110 is now summarized. During the pipe making cycle, prior to actuation of slump filler 82, hydraulic pressure is supplied to ram units 110 with sufficient force to overcome the holdown force from cylinders 32 (FIG. 4). As the pipe is vibrated at the end of the cycle (FIG. 5), pressure is relieved from ram units 110, thereby allowing hopper 28 and slump filler 82 to lower under force of holdown cylinders 32. After a pipe 80 is finished and hopper 28 is lifted from jacket 74 by struts 24 engaging lift blocks 40 on lift rods 38 (FIG. 1) so that turntable 42 may be rotated to provide a new jacket 74, top centering ring 108 will fall away from filler ring 104 to the extent permitted by posts 116 (FIG. 6). Of course, before holdown cylinders 32 are reactuated to secure a new jacket 74 in place ram units 110 will be fully extended so the slump filler 82 will be in a ready state as a new pipe making cycle begins.

Turning now to FIGS. 9-16, use of the slump filler with a closed bore cap 132, having a snap ring 134 therein, will be discussed. When slump filler 82 is used with open bore caps, compaction ring 96 acts directly upon the material forming the outer spigot end of pipe 80, as explained previously, open bore cap 98 remaining stationary during operation of slump filler 82 (FIGS. 4-5; 6-7). Cap 98 is retained in a stationary position by a series of retractable support pins 136 through the side wall of jacket 74. (When a completed pipe 80 is being cured, jacket 74 is removed soon after the pipe 82 is formed, but cap 98 remains in place until curing is complete. Thus, retractable pins 136 permit jacket 74 to be removed without disturbing cap 98). However, when slump filler 82 is used with a closed bore cap 132, the entire cap must be moved from an upper to a lower position (FIGS. 9 and 10) since there is no room for a compaction ring 96 to fit between core

62 and the inner peripheral edge of closed bore cap 132.

Therefore, retractable closed bore cap rest means must be provided to hold closed bore cap 132 in an elevated attitude during initial formation of pipe 80, but be withdrawn, automatically, when slump filler 82 is actuated. The preferred structure is a series of cap rest assemblies 138 (FIGS. 11-13) which is also disclosed and is claimed in the copending application hereinbefore identified, Ronald J. Walchek, inventor. In a preferred embodiment, three equispaced cap rests 138 are sufficient, but more may be added if necessary.

Cap rest assembly 138 has a mounting 140 welded to the side wall of jacket 74 near the upper end of the jacket, a pair of torsion springs 142 located upon a torsion spring mounting and retainer bolt 144, one spring to each side of mounting 140, a pair of set screws 146 abutting the free ends of springs 142, and a base 148 to secure the other ends of torsion springs 142. A cap rest foot 150 is pivotally mounted centrally of mounting 140 and extends through an opening 152 out through jacket 74, when supporting closed bore cap 132 (FIG. 11).

Slump filler 82 includes a slump compression ring 154 at its lower end, instead of compaction ring 96. However, both ring 96 and 154 are substantially alike in function and dimensions, save for the fact that ring 154 contacts the top of closed bore cap 132 whereas ring 96 contacts the concrete forming the outer spigot end of the pipe directly. In other words, the only real difference between construction and operation of the slump filler arrangement when used with closed bore and open bore caps is substitution of cap rest 138 for pins 136 in the former, and use of pins 136 in place of cap rests 138 in the latter.

Prior to actuation of slump filler 82, cap rest feet 150 support closed bore cap 132 as shown in FIG. 11, springs 142 being adjusted as needed by set screws 146 to support the weight of closed bore cap 132. When slump filler 82 is actuated, closed bore cap 132 moves downwardly to the position indicated in FIG. 12, thereby pivoting cap rest feet into a retracted position, there being sufficient force from holdown cylinders 32 (FIG. 4) to overcome force exerted by torsion springs 142.

The invention is useful in the production of a wide variety of unreinforced and wire reinforced pipe. It may even be used in the production of non-cylinder concrete pipe, non-prestressed, which has been used extensively in the water supply industry for low-head transmission lines. (See American Water Works Association Manual M9, New York, 1961:pp.4-5). A section of such pipe is shown in FIG. 14, and includes a lower bell ring 156 welded to lower, wire cage reinforcement 158, and an upper spigot ring 160, seamed to upper wire cage reinforcement 162. In this case, a Z-closed bore cap 164 is employed, but the remaining elements of the machine remain as before. Reinforcement sections 156-158 and 160-162 are situated in telescoping relationship, unconnected one to the other, so that slump filler 82 may be used as disclosed in FIGS. 11-13 and discussed above.

An earlier development of a closed bore cap support is shown in FIGS. 15 and 16. A mounting bracket 166 has a cap support pin 168 slidably mounted therein, biased to a closed bore cap support position (as shown in solid lines, FIG. 16) by a torsion spring 170 bearing against one leg of a lever 172 having its fulcrum at bolt

174. The other leg of lever 170 is connected to support pin 168 by a pin 175. A hydraulic actuator 176 is secured beneath top centering ring 108 (not shown in FIGS. 15 and 16) and is actuated to retracted support pin 168 to the position shown in FIG. 16 upon actuation of the slump filler (not shown in FIGS. 15 and 16). Pin 136 which is employed with open bore caps is removed when closed bore caps are used, but a mount therefor is provided on bracket 166 so that the device may be used with open bore caps. Conversely, support pin 168 is not used when pins 136 are in use.

The previously discussed cap rest assembly 138 is preferred because, being entirely mechanical in nature, it does not require extra actuation means such as actuator 176.

Similarly, an early development in finding an adequate slump filler apparatus is disclosed in FIGS. 17-19. In other words under ideal field conditions, the slump filler disclosed in these Figures will operate satisfactorily, but the embodiments disclosed previously have proven to be far more reliable, particularly in varied use conditions.

In this early embodiment, hopper 28 and top centering ring 108 are secured together, instead of being spaced apart by hydraulic ram actuators and moved together under influence of the holddown cylinders to actuate slump filler 82. In this case, slump filler 82 is mounted within the confines of hopper 28 and arranged for spiral movement instead of linear, vertical actuation. Specifically, filler ring 104 of slump filler 82 is bolted about its periphery to a driven, slump filler actuating ring 178, having an outer circumferential base flange 180 attached to at least a pair of hydraulic piston-cylinder actuators 182. Actuators 182 are mounted at their cylinder base ends to struts 184 which are welded to formed extensions (FIG. 17) of hopper bottom plate 106. Actuators 182 and attendant parts are protected from concrete and other debris by a stationary cover plate 186, having an internal depending flange which overlaps the vertical side walls of actuating ring 178. FIG. 17 illustrates the relationship of parts, with the main side wall of hopper 28 removed so that the interior may be viewed clearly.

FIG. 18 shows one of the two actuators 182 together with one of two cam assemblies 188 employed with each actuator 182. In this view, flange 180 and consequently slump filler 82 attached to ring 178 are in a raised attitude. Cam assembly 188 has a cam 190 comprising a pair of bars welded to a vertically disposed plate 192, which is in turn welded to hopper bottom plate 106. A cam follower or roller 194 on roller mount 196, welded to flange 180, is disposed to ride in cam 190; a pair of rollers 198 may be added to roller mount 196 to assure integrity of the moveable arrangement.

The free piston end of actuator 182 is secured to weldment ear 200 of flange 180 by a pin bolt 202, while the cylinder base end of actuator 182 is attached to struts 184 by a second pin bolt 204 through a crossbar weldment 206 between struts 184. Both actuator 182 and cam 190 are arranged in parallel planes, angled to a horizontal plane so that flange 180, slump filler actuating ring 178 and slump filler 82 move downwardly in a spiral or helical fashion to form the spigot end of pipe 80. FIG. 19 illustrates disposition of elements after compaction ring 96 of slump filler 82 has completed its function. Although this embodiment of the invention is illustrated in used with an open bore cap 98, it could easily be adapted for use with closed bore caps, as pre-

viously set forth above with respect to the first embodiment of slump filler 82.

While this embodiment of the invention has certain advantages, namely slump filler 82 may be actuated without aid of the holddown cylinders of the machine and imparts a spiral action to compaction ring 96 which, when used with an open bore cap 98, serves to trowel and smooth the outer end of the pipe spigot end, it is more expensive to produce and requires substantial maintenance for satisfactory operation. For example, the actuating mechanism is located interiorally of hopper 28, rather than at the bottom and outside of hopper 28, thus leaving little room for a hopper cleaner (not shown), a well known mechanism in the art usually comprising a pair of spiral segments periodically activated to sweep accumulated excess concrete from the hopper.

A detail discussion of pipe making methodology in a packerhead/vibration system follows, with particular attention to the operation of a slump filling step included in the operation. Preparation for a pipe making cycle begins with placing an empty pipe jacket on turntable 42 in the off bearing position and rotating turntable 180° to place the jacket in a pipe making position beneath the crosshead (FIG. 2). Of course, when the operation is in progress a jacket with a completed pipe in place in the pipe making position will be rotated simultaneously to the off bearing position to be removed for curing and replacement by a fresh, empty jacket. During this time, rollerhead 64 is fully raised (FIG. 3) and core 62 is completely lowered into pit 12 so that turntable 42 may be rotated.

The pipe making cycle begins by lowering rollerhead 64 down into pipe jacket 74 until the bases of the rollers of rollerhead 64 are situated immediately above the top flange of pipe bell end pallet 76. Core 62 is raised sufficiently so that rollerhead-vibrating core locking device 92 may latch rollerhead and core together. Bell down unit 78 is also raised so that table and vibrating assembly 95 engages bell pallet 76 to rotate the same, clockwise (viewed downwardly) and vibrate pallet 76 as concrete is introduced to jacket 74 from boot 56 and conveyor 58. After concrete is placed in the bell, rollerhead 64 is rotated counterclockwise (also viewed downwardly) and this counterrotation of pallet 76 and rollerhead 64 is continued until the bell of the pipe is formed.

Next the rotating rollerhead 64 and the non-rotating vibrating core 62 in combination arrangement are raised as concrete continues to be added to jacket 74 to form the major section of the pipe. During this phase of the complete cycle, vibration and rotation of pallet 76 ceases and bell down unit is lowered to its initial position (the lowermost disposition of bell down unit 78 is shown in FIG. 3). Vibration of the core consolidates concrete forming the pipe, eliminates voids and relieves residual toroidal stress in any reinforcing wire in the pipe (not shown, except in FIG. 12) to induce a more intimate bond between reinforcement and concrete.

Eventually, all concrete will have been introduced into jacket 74 and the machine will reach a phase illustrated in FIG. 3, where rollerhead 64 has ceased rotation, and has been detached from core 12 and raised above the jacket. However, some customers prefer to make a second or even third "pass" of rollerhead and core within jacket 74 so that a little more concrete may be added and an even more dense pipe may be formed.

11

In this case, rollerhead and core will remain locked together and lowered to the bottom of the jacket to be raised again, the rollerhead rotating and core vibrating, as a little more concrete is introduced into jacket 74. In such multiple pass operations, bell down unit 78 will not be reactivated after the first pass.

For actuation of slump filler 82, core and rollerhead may remain locked together or separated as described (FIGS. 3 and 5), the latter course being more common. During actuation of slump filler 82, core 62 continues to vibrate while material already in jacket 74 is compacted by the slump filler to reduce the overfill 84 (FIG. 4) into a completed pipe 80 (FIG. 5) and correctly form the spigot end of the pipe.

When the pipe is finished, core and rollerhead are unlocked, with raising of the rollerhead if this has not already been done, and core 62 is fully retracted into pit 12. Thereafter the complete pipe making cycle is repeated as just described.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. A packerhead/vibration system for making pipe of cementitious material in one continuous operation comprising: pipe form means; means for introducing cementitious material into said pipe form means; a rotating packerhead, upwardly moveable through said pipe form means for making the pipe; means for vibrating the cementitious material comprising the pipe as the pipe is made; means for enabling overfilling said pipe form means with an overfill of the cementitious material and being located on said pipe form means as the pipe is made; means for compressing said overfill into said pipe form means to complete the end of a green pipe; and means on said pipe form means for positioning said overfill compressing means in a first predetermined location as the pipe is made and in a second predetermined location beneath said first predetermined location after said overfill is compressed into said pipe form means to complete the end of a green pipe.

2. The packerhead/vibration system as recited in claim 1 wherein said pipe form means comprise a generally cylindrical and vertically disposed jacket having pipe bell end forming means at the lower end thereof and pipe spigot end forming means at the upper end thereof, said overfill compressing means and said means for positioning said overfill compressing means both surmounting said pipe spigot end forming means.

3. The packerhead/vibration system as recited in claim 2 wherein said pipe form means further comprise a hopper surmounting said spigot end forming means, said means for compressing said overfill into said pipe and said means for positioning said overfill compressing means both being mounted on said hopper.

4. The packerhead/vibration system as recited in claim 3 wherein said hopper further comprises a stationary top centering ring located concentrically downwardly of said hopper, positionable on the upper outer periphery of said pipe form during a pipe making oper-

ation, and removable therefrom with said hopper after a pipe making operation.

5. The packerhead/vibration system as recited in claim 4 wherein said overfill means and said overfill compressing means are arranged concentrically, one with respect to the other, and generally between said pipe form upper outer periphery and said hopper.

6. The packerhead/vibration system as recited in claim 5 wherein said overfill compressing means comprise an overfill compression ring, rigidly mounted on and depending concentrically downwardly interiorally from said hopper, releasable spacer means separating said hopper and said top centering ring, and hopper holdown means, operative to move said hopper and overfill compression ring downwardly with respect to said top centering ring and said pipe form to compress said overfill into said pipe form spigot end.

7. The packerhead/vibration system as recited in claim 6 wherein said spacer means comprise a plurality of circumferentially spaced fluid pressure actuators.

8. The packerhead/vibration system as recited in claim 7 wherein each of said fluid pressure actuators comprises a piston cylinder actuator.

9. The packerhead/vibration system as recited in claim 8 wherein said each of said plurality of piston cylinder actuators further comprises adjustable stop means for adjustably preselecting the separation distance between said hopper and said top centering ring.

10. The packerhead/vibration system as recited in claim 9 wherein said adjustable stop means comprises at least a pair of posts depending from said hopper on opposite sides of said actuator and projecting through said top centering ring, each post having stop means at the lower end of said post, beneath said top centering ring and arranged to abut the lower surface of said top centering ring, and releasable securing means on said post beneath said stop means for adjusting the location of said stop means along said post.

11. The packerhead/vibration system as recited in claim 6 wherein said pipe form means further comprise an open bore cap ring at the spigot end thereof, arranged to form approximately one-half of the outer spigot end of the pipe, means for securing said open bore cap ring at the top of said pipe form means, beneath said top centering ring, said overfill means comprising a vertically arranged relatively short length cylindrical spacer ring mounted on the inner peripheral edge of said top centering ring, said overfill compression ring being arranged concentrically interiorally of said overfill means spacer ring and movable downwardly therewithin to compact said overfill into said pipe form means.

12. The packerhead/vibration system as recited in claim 11 wherein said means for securing said open bore cap ring in said pipe means comprise a plurality of circumferentially spaced retractable support pins, located through said pipe form, substantially beneath said open bore cap ring.

13. The packerhead/vibration system as recited in claim 11 wherein said overfill means spacer ring further comprise means defining a plurality of passage means adjacent the upper periphery thereof, for discharge of cementitious material exceeding desired amount of overfill.

14. The packerhead/vibration system as recited in claim 11 wherein said overfill means spacer ring is arranged between said hopper and said top centering ring to limit the approach of said hopper and top centering

ring together during a pipe making operation.

15. The packerhead/vibration system as recited in claim 6 wherein said means for overfilling the pipe form means comprise a closed bore cap ring at the spigot end of said pipe form means, arranged to form substantially the entire outer peripheral end of the pipe spigot end, and releasable support means to support said closed bore cap ring above the upper end of said pipe form, said overfill compression ring being located above said closed bore cap ring and arranged to press said closed bore cap ring and said overfill therebeneath into said form means to complete the spigot end of the pipe.

16. The packerhead/vibration system as recited in claim 15 wherein said top centering ring includes a short length cylindrical spacer ring for limiting axial approach of said hopper and said top centering ring.

17. The packerhead/vibration system as recited in claim 16 wherein said short length cylindrical spacer ring further comprises means defining a plurality of passage means along the upper periphery thereof, for discharge of excess cementitious material there-through.

18. The packerhead/vibration system as recited in claim 5 wherein said hopper and said top centering ring

are rigidly secured together, said overfill compressing means comprising an overfill compressing ring, located concentrically downwardly interiorly of said hopper, actuating ring means, located interiorly of said hopper, said overfill compression ring depending therefrom, and fluid pressure actuating means mounted in said hopper for moving said actuating ring means and overfill compression ring vertically downwardly towards said pipe form means.

19. The packerhead/vibration system as recited in claim 18 wherein said fluid pressure actuating means for moving said actuating ring means and overfill compression ring comprise at least a pair of piston cylinder actuators, located on opposite sides of said hopper.

20. The packerhead/vibration system as recited in claim 19 wherein each of said pair of piston cylinder actuators is arranged at an angle to a horizontal plane and further comprises cam means mounted on one of said actuating ring means or hopper and cooperating cam follower means mounted on the other of said actuating ring means or hopper whereby upon actuation of said piston cylinder actuators, said actuating ring means and overfill compression ring means are driven spirally downwardly towards said pipe form means.

UNITED STATES PATENT OFFICE
CERTIFICATE OF CORRECTION

PATENT NO. : 3,922,133

DATED : November 25, 1975

INVENTOR(S) : Gerald R. Crawford and Joseph F. Wenther

It is certified that error appears in the above-identified patent and that said Letters Patent are hereby corrected as shown below:

Column 3, line 37, delete the comma after "6".

Column 5, line 9, change "packer-shaft" to
--packershaft--.

Column 5, lines 11 and 12, delete "The 'Viropac'
non-rotating core is mounted beneath turntable 14".

Column 6, line 48, change "bolded" to --bolted--.

Column 9, line 67, change "used" to --use--.

Signed and Sealed this
sixth Day of April 1976

[SEAL]
